FLUID DISPENSER

Original Filed July 27, 1923

UNITED STATES PATENT OFFICE

REX G. HAMAKER, OF HOUSTON, TEXAS.

FLUID DISPENSER.

Application filed July 27, 1923, Serial No. 654,068. Renewed March 5, 1929.

This invention relates to new and useful improvements in a fluid dispenser.

One object of the invention is to provide a dispenser for gasoline, oils, or other fluids, and which may be operated to discharge a predetermined quantity of the liquid, through the instrumentality of a coin inserted into a suitable coin slot, provided for the purpose, said coin constituting the purchase price of 10 the quantity to be delivered.

Another object resides in the provision of an apparatus of the character described which is normally locked against operation, so that no delivery can be made until a coin of the 15 proper denomination is placed in the coin slot and which becomes an element of the apparatus to permit the actuation thereof, to effect delivery.

Another feature of the invention resides 20 in the provision of means for regulating the amount of the liquid delivered, so that as the price of the merchandise varies, the quantity delivered for any fixed price may be correspondingly varied.

25 With the above and other objects in view, the invention has particular relation to certain novel features of construction, operation, and arrangement of parts, an example of which is given in this specification and 30 illustrated in the accompanying drawings, wherein:—

The figure shows a vertical sectional view of the device.

In the drawings the numeral 1 designates 35 a suitable housing for the operative mechanism. Mounted on this housing there is a fluid container 2, constituting a measuring chamber. The numeral 3 designates a supply tank, preferably underground in which 40 the fluid to be dispensed is under pressure. A supply line 4 leads up from the supply tank 3. The upper section 4' of this pipe enters the bottom of the measuring chamber 2 through a gland 5, and the lower end of this section 45 telescopes in the supply line 4 through the gland 6. There is an overflow line formed of the lower and upper sections 7 and 7', the former of which is connected to, and upstands from, the tank 33, and the latter of which extends through the gland 8, in the bottom of the measuring chamber and has its lower end telescoping in the section 7 through the gland 9, said glands 5, 6, 8, and 9, forming fluid tight joints.

55 There is a clamp 10 fastened to the sections 4' and 7', one side of which is formed with a

rack face 10' which is in mesh with a spur gear 11, fixed on the shaft 12. This shaft is rotatable in suitable bearings in a frame 13, and may be rotated by the crank 14 to move the 60 bracket 10, and the pipe sections to which it is secured, up or down, said pipe sections working through the glands above described.

A discharge or service line 15 leads from the bottom of the measuring chamber 2, and preferably terminates in a flexible hose 16.

The supply and discharge lines are controlled by suitable cut-off valves 17 and 18 respectively, of conventional construction, and actuated through the respective stems 19 and 20. Actuating levers 21 and 22 are provided, the former of which has a sliding pivotal connection, at its upper end, with the stem 19 and at an intermediate point is pivoted to the bracket 23, which is fixed to the casing 75 of the valve 17, and the latter of which is pivoted at its upper end to a bracket 24, fixed to the casing of the valve 18, and at an intermediate point has a sliding pivotal connection with the stem 20, the lower ends of each of 80 said levers being free. Coil springs 25, and 26, are attached at one end to the free ends of said levers, and at their other ends they are anchored to fixed anchors above the pivotal points of attachment, of said levers to said 85 brackets.

Attached to the upper end of the inlet or supply pipe there is a valve casing 27, whose upper end has a valve seat 28, which is controlled by the downwardly opening valve 29 90 which is attached to the lower end of the valve stem 30. There is a lever 31, pivoted at one end to the upper end of the overflow line and attached to the other end of this lever there is a float 32. The valve stem is pivotally connected at its upper end to the lever 31.

When a predetermined amount of the liquid to be dispensed enters the measuring tank, the float will be elevated, and the valve 29 thereby closed. Should there be any 100 leakage past said valve, or an excess liquid in any way enter the measuring chamber, the excess will overflow back into an overflow tank 33, through the overflow line. If the price of the commodity should increase, a 105 smaller quantity should be delivered, for a fixed price, and to bring this about the crank 14 is turned to lower the sections 4' and 7', in the measuring tank, and vice versa.

The overflow tank 33 is connected into the 110 supply tank 3 by means of a relief line 34, which is controlled by a downwardly open-

ing relief valve 35 which is normally held closed by the pressure from the tank 3. At intervals the pressure may be cut off from said tank 3, and thereupon the valve 35 will open 5 and the contents of the overflow tank will drain into the supply tank 3.

The numeral 36 designates a manually operable valve actuating push bar, which is 10 slideable in the long bearing 37 in the housing, and whose outer end projects out from the front side of said housing and is formed into a push knob 38. A coil spring 39 is interposed between said knob and the housing, and surrounds the projecting end of 15 said bar. This bar is formed with a shoulder 40, and there is a pivoted spring actuated latch 41 formed with a shoulder 42, spaced from, but in position, normally, to interlock with the shoulder 40, to lock the 20 bar 36 against operation. There is a coin chute 43 in the housing which normally aligns with a side notch 44, in the bar 36, and when a coin, as 45, is inserted in the chute, it will drop into said notch, and upon actuation of the bar 36, the coin will contact with the upwardly beveled free end of the latch 41, and lift said latch to permit the further actuation of said bar.

There is a manually operable valve reversing bar 46, slideable in suitably aligned bearings, and one end of which projects out from the front side of the housing and is formed with a push knob 47, and interposed between said knob, and the housing, and surrounding the projecting end of said bar 35 there is a spring 48.

In operation the valve reversing gear 46 is first operated and the levers 21, and 22, are thereby moved from the positions indicated in dotted lines, to positions indicated 40 in full lines by the lugs 49 and 50, carried by said bar 46.

The push bar 46 is then returned by the action of the spring 48, and the parts assume 45 the position as shown in full lines in the drawings. The valve 17 is now open and the valve 18 is closed and the measuring chamber 2 will now fill and lift the float 32. When the required amount of liquid is in the measuring chamber, the float will lift the valve 29, and shut off the supply, any surplus that may have entered said chamber draining off 50 through the drain pipe, as heretofore explained. The coin is now inserted and the bar 36 actuated. There is a cross link 51 operable on a fixed pivot 51' intermediate its ends and the upper end of this link is connected to the bar 36. The lower end of link 51 is pivoted to the sliding bracket 52. When the 55 bar 36 is actuated, it will move said bracket in the opposite direction, and the lugs 53 and 54, carried thereby, will contact against and actuate the levers 21 and 22, in reverse direction. When the springs 25, and 26 pass center 60 65 they accelerate the movement of the valves

and cause a quick action thereof. The valve 17 is now closed, and the valve 18 is opened, the position of the lugs 53 and 54, relative to said levers being such that valve 17 will close before valve 18 opens. The liquid in the 70 measuring chamber will now be discharged through the service line and delivered to the customer.

There is a safety lock consisting of the locking rod 55, which has a sliding pivotal connection at its upper end with the latch 41, and is vertically slideable in suitable bearings, provided for it, the lower end 56 forming a lock bolt. When the latch 41 is lifted, this bolt seats in an aligned notch 57, cut 75 in the underside of the bar 46, and locks said bar against a second operation until the bar 36 has been returned to initial position, thus completing a cycle of movement.

Within the measuring chamber there is a 85 vertical gauge 58 by the use of which the overflow pipe may be accurately adjusted as is required on account of price variations, and on the outside of said chamber there is a 90 similar gauge 59 for the inspection of customers.

The coin 45, upon actuation of the bar 36 is moved into alignment with the coin delivery chute 60, and passes therethrough, and falls into the coin receiving receptacle 61 provided to receive it.

What I claim is:

1. A liquid vending machine including a measuring chamber, an inlet line and a discharge line connected into said chamber, said inlet line being extensible, valves controlling said lines, manually operable means for actuating said valves approximately simultaneously, one into open and the other into closed position, manually operable means through 105 which said valves may be actuated into reverse position, means associated with said inlet line in said chamber and actuated by the fluid in said chamber and operating to limit the amount of fluid entering the chamber, means for varying the extension of the 110 inlet line into said chamber, to vary the position of said limiting means in said chamber to thereby vary the quantity of fluid which is permitted to enter the chamber. 115

2. A liquid vending machine including a measuring chamber, an inlet line and an overflow line entering said chamber, said overflow line projecting up into the chamber and being adjustable therein to vary the amount 120 of liquid retained in said chamber, a discharge line, valves controlling said inlet and discharge lines, manually operable means through which said valves may be actuated to close one of them and open the other, manually operable means for actuating said valves to reverse the same, a releasable locking device for alternately locking and releasing said respective means.

3. A liquid vending machine including a 125

measuring chamber, an inlet line and a discharge line connected into said chamber, valves controlling said lines, manually operable means through which the valves may be actuated to open the inlet line and close the discharge line to permit said chamber to fill, manually operable means actuating said valves into reversed position to permit said chamber to empty, releasable locking devices alternately locking said respective valve actuating means in locked position, and means limiting the amount of liquid entering said chamber to a predetermined quantity.

4. A liquid vending machine including a measuring chamber, an inlet line and a discharge line connected into said chamber, valves controlling said lines, manually operable means through which the valves may be actuated to open the inlet line and close the discharge line to permit said chamber to fill, manually operable means actuating said valves into reverse position to permit said chamber to empty, a releasable locking device normally locking one of said manual means in locked position, and means limiting the amount of liquid entering said chamber to a predetermined quantity, said limiting means being adjustable to vary said predetermined quantity.

In testimony whereof I have signed my name to this specification.

In testimony whereof I have signed my name to this specification.

REX G. HAMAKER.
